UNITED STATES PATENT OFFICE.

ARNOLD HENRY SAVAGE LANDOR, OF FLORENCE, ITALY.

AIRSHIP.

1,239,796.

Specification of Letters Patent. Patented Sept. 11, 1917.

Application filed April 23, 1917. Serial No. 164,047.

To all whom it may concern:

Be it known that I, ARNOLD HENRY SAVAGE LANDOR, a subject of the King of Great Britain and Ireland, and residing at Florence, Italy, have invented certain new and useful Improvements in and Relating to Airships, of which the following is a specification.

The present invention relates to airships of the type in which a rigid framework of depth greater than its width is associated with a number of separate gas-containing compartments arranged with their axes vertical.

The object of the present invention is to provide an improved construction of the type indicated, which shall give among other advantages simplicity and rapidity of construction, great rapidity of maneuver, great speeds, freedom from rolling and pitching, offer a small target when viewed from below or above and provide abundant buoyancy in case of damage, and permit the firing of guns mounted beneath the airship at objects vertically above or below the airship.

The present invention consists broadly in an airship of the type indicated, in which the framework is in the form of a girder whose depth is considerable in relation to its width and is a maximum toward the forward end, tapering to a point at the bow and slightly tapering toward the stern, while in plan also the airship is broad toward its bow and narrow toward its stern, the gas compartments being in the form of one or more ranks of cylinders or similar shapes, the axes of which are vertical when the airship is horizontal, so that in plan and cross section a substantially stream-line outline is provided.

The invention further consists in providing improved means whereby the lower portion of the gas cylinders can be compressed either automatically or under hand control, to accommodate the reduced volume of the gas due to reduction of barometric pressure or temperature or diffusion.

The present invention further consists in providing a rudder at each of the extreme ends of the framework, the rudder at the bow being composed of two pivoted portions.

The invention further consists in providing a propeller on each side of the airship, and one or more further propellers in rear of the first, each succeeding propeller being

situated at a greater distance from the side of the airship than the preceding one.

The invention further consists in mounting guns on platforms so constructed that they can be fixed or else made to swing or telescope out when in action or rest alongside the airship so as not to interfere with her speed, and which extend from the lower portion of the sides of the framework, in such a manner that the guns can be fired at objects vertically above or below the airship.

A gun can also be mounted at the forward end of the gondola.

At the extreme lower point aft of the airship a small observation platform may be provided on which a light machine gun may be mounted and a searchlight; this would protect it from attacks by aeroplanes from behind, above, below or at the sides.

The present invention further consists in the improved airship hereinafter described.

Referring to the accompanying drawings:

Figure 1 is a diagrammatic elevation showing one form of the present invention.

Fig. 2 is a plan of Fig. 1.

Fig. 2^a is a plan showing an alternative form in which cylinders are made of the same cross-section throughout the length and are of hexagonal and triangular sections.

Fig. 2^b shows in plan further alternatives.

Fig. 3 is a detail on an enlarged scale of one form of framework.

Fig. 4 is a cross-section of Fig. 3.

Fig. 5 shows alternative methods of compensating for diminished volume of gas.

Fig. 6 illustrates the large field of fire of the guns.

Fig. 7 shows a machine gun and mounting.

Fig. 8 shows some of the alternative profiles which may be employed for the aerostat.

Fig. 9 is a detail view showing the swinging gun platforms.

Fig. 10 shows a form of telescoping gun platforms; while

Fig. 11 is a detail view showing the aft observation platform.

In carrying the present invention into effect, according to one form and as shown in Figs. 1-4, there is provided a framework *a*, *b*, *c*, composed of any suitable material, for example, steel or aluminium, wood or bamboo with any suitable form of joint. This framework is in the form of a deep narrow girder of substantially fish-shaped outline tapering to a point at the bow and

gradually tapering toward the stern from the point of maximum depth which is near the forward end (see Fig. 1) and may be composed, for example, of tubes or suitably sectioned rolled or stamped material, and braced as for example by wires d in such a manner as to provide longitudinal stiffness in a vertical and horizontal plane.

In the central plane of this framework, 10 cylindrical gas compartments e are arranged, the diameter of the cylinders being approximately equal to the width of the girder, so that the cylinders are of substantial length as compared with their diameter. A single 15 or more rows of such gas cylinders may be provided in the central plane of the airship, and at the forward end a further row or rows on either side of the central row or rows, or if desired, the diameter of the cylinders may be varied as shown in Figs. 2 and 2^b when extra cylinders of any suitable section are employed to fill up spaces.

In order to obtain the maximum gas capacity the space between the large cylinders 25 may be filled in by small diameter cylinders e' ; or gas bags elliptical in section may be employed as shown at the right-hand side of Fig. 2^b.

It will be understood that the gas bags 30 may be more or less flattened throughout their length so that their cross-section approximates to a hexagonal, octagonal elliptical or other suitable form to give the greatest possible gas capacity for given over-all 35 dimensions of the aerostat.

Such a construction is illustrated in Figs. 2^a and 2^b in which modified constructions the gas bags e are made of hexagonal section and the smaller gas bags e' of triangular 40 or circular section.

The outer row of gas cylinders may conveniently be of less length than the central row, in order that the cross-section of the airship may approximate to a stream-line 45 cross-section, or the lower and upper portions of the cylinder may be of decreasing diameter for the same purpose as shown in Figs. 4 and 5.

Any suitable means are provided to support a suitable outer envelop of fabric, celluloid or the like, mica, thin metal, or other suitable material, in order that the framework and gas compartments may present an unbroken and continuous surface, 55 for the purpose of reducing air friction.

All the gas cylinders are preferably connected to a common gas main as at y (Fig. 5). They may be connected in groups if desired, or else each one may be a separate 60 unit.

At each end of the framework rudders f and g are provided. The rudder g at the stern may comprise a large plane surface, mounted on a vertical hinge, and adapted to 65 swing through a very considerable arc on

either side of the central plane of the airship with or without simultaneous warping. At the bow a pair of planes f may be provided, pivoted upon vertical hinges, and so arranged that they can be swung within the framework, or projected on either side, the hinge being so arranged that the planes trail with respect to the hinge. These planes f , f , are preferably fixed at a definite angle with respect to one another. In proximity 75 to the bow and stern rudders elevating planes h and k may be provided, and further elevating planes j may be provided at one or more intermediate points along the main frame.

It is to be noted that by providing the plane h (either single, or composed of several parallel planes) at the extreme forward end of the airship, a very powerful and sensitive control of the upward and downward 85 inclination of the ship is provided.

Beneath the forward end of the airship, in the region where three or more ranks of gas cylinders are employed, or where the diameter of the cylinders is large, a gondola 90 l is provided of any required length carrying the engines, wireless plant, searchlight, bomb and aerial torpedo launching appliances, etc., and providing accommodation for the crew. The gondola carries forward 95 a gun so placed as to have an unobstructed field in front, at the sides and vertically below. The gondola may be built in the lower part of the framework a and a passageway may be provided the whole length of the 100 ship in the part a .

At the sides of the framework, suitable brackets m are provided, carrying propellers n . Two or more pairs of propellers are provided. The propellers on each side are 105 so arranged that each succeeding propeller is situated at a greater distance from the side of the airship than the preceding propeller so that the wash of the preceding propeller shall not interfere with the propeller immediately behind it, and therefore a greater propeller efficiency can be obtained 110 (see Fig. 2).

Below the rear portion of the airship suitable platforms o are provided, projecting on either side of the lower part of the framework, and upon these platforms guns p are mounted. The effect of this arrangement is that the guns can be fired at objects vertically above the airship, without requiring to be mounted on the top part of the airship framework.

It is obvious that the same guns may be fired vertically downward, or in any direction to either side of the airship (see Fig. 6).

There may also be provided an aft observation platform 1, carrying a searchlight 2, and machine gun 3, as illustrated in detail in Fig. 11. The gun platforms p may also be constructed so that when not in action 130

they can be swung or telescoped back along side, or under the part *a* of the airship. This can be effected either by mounting the platforms on swinging arms *o* as shown in Fig. 9, or on brackets *o'* constructed on the lazy tongs principle as illustrated extended at Fig. 10.

On the upper and lower portions of the main framework, stationary fins *g* may be provided, to increase the stability of the airship, and also along the sides of the airship.

It will be understood that owing to the elongated cylindrical construction of the gas chambers, when diminution of gas occurs, the remaining gas always tends to collect in the upper part of each gas chamber, so that the center of buoyancy is always situated near the upper part of the airship.

In order to accommodate the size of the gas chambers to the volume of gas contained within them, means are provided to compress the lower portions of the cylinders. This may be effected (see Fig. 5) for example, by providing a pair of rods *r* upon either side of each rank of cylinders, the rods being arranged so that they can be brought together to nip the cylinders when required, and mechanism being also provided to raise and lower each pair of rods, so that the nipping can be applied at the required point of each cylinder. As an alternative, the cylinders of each rank may be connected at their lower ends to a common roller, provided with means whereby it can be rotated, either automatically or by hand, so that that portion of the gas compartment which is not occupied by gas can be rolled up by rotating the roller.

As a further alternative, a ring or perforated disk *t* may be provided internally at the mouth of the cylinder, and this may be attached by cords *s* with cords *u* passing over pulleys suspended from the top of the cylinder which is in its turn attached to the framework and carrying weights *v*. As the volume of the gas decreases the weight pulls up the slack part of the cylinder.

Again, in a further modification an arrangement of draw strings may be provided at intervals up the cylinder so that the capacity may be regulated by constraining the mouth of the cylinder.

According to a further modification a contracting ring *w* may be arranged so that it can be applied at the desired point in the length of the cylinder.

All the devices described for adjusting the volume of the gas-containing cylinders may be arranged to automatically adjust the volume or may be arranged to be adjusted by hand.

In addition to the propellers already described additional tractor propellers may be provided.

According to a modification the rear rud-

der *g* may be arranged so that it can be warped in such a manner as to increase its controlling effect.

In all the forms described suitable floats *x* may be provided under or along the gondola under the swinging gun platforms and along the lower portion of the airship framework to support the airship when a descent is made upon water.

It will be appreciated from the foregoing description that the constructions contemplated have among others the following advantages:—

Owing to the center of buoyancy being always situated toward the upper part of the airship, greater freedom from rolling and pitching is obtained than with the known constructions. Owing to the narrow aspect of the airship in plan it offers a small target when fired at from above or below and this narrowness also permits the firing of the guns mounted beneath the airship at objects vertically above or below the airship. Owing to the narrow shape of the airship and the special disposition of the propellers great speed can be attained. Great rapidity of maneuver either to go up or down, or quick lateral revolutions can be obtained by the special disposition of the frontal elevating planes and rudders acting in conjunction with the rear ones.

The arrangement is such that the framework may be easily adapted so that it can be both dismounted and put together with rapidity and ease to facilitate transport, repairs, etc.

Further, owing to the plan section of the airship being broad at one end and narrow at the other, two such airships may be housed in a single shed of moderate width, where there would be room for only one airship of other existing shapes.

A further advantage of the construction described is that owing to the large number of gas chambers into which the airship is divided, it is rendered practically indestructible so far as perforation by bullets and shell fragments are concerned, as a large number of the chambers can be damaged without reducing the buoyancy sufficiently to bring the airship down.

It will be seen that many modifications may be made in the method of carrying the present invention into effect without departing from the spirit of the invention.

Having now described my invention, what I claim as new and desire to secure by Letters Patent is:—

1. An airship of the type indicated in which the framework is in the form of a girder whose depth is considerable in relation to its width, and is a maximum toward the forward end tapering to a point at the bow and slightly tapering toward the stern, while in plan also the airship is broad to

ward its bow and narrow toward its stern, the gas compartments being the form of one or more ranks of substantially cylindrical bodies, the axes of which are vertical when the airship is horizontal, the gas compartments being so arranged that in plan and cross-section a substantially stream-line contour is provided, substantially as described.

2. In an airship as claimed in claim 1
10 means for compressing the lower portions
of the gas cylinders in order to accommo-
date the reduced volume of the gas due to
increase of barometric pressure or reduction
15 of temperature or diffusion, thus doing
away altogether with the internal air bal-
loonets now in general use, substantially as
described.

3. In an airship as claimed in claim 1,
20 a rudder at each of the extreme ends of the
girder framework, the rudder at the bow

being composed of two portions pivoted
about a common axis and an elevating plane
on the nose of the airship.

4. In an airship as claimed in claim 1,
25 having a propeller on each side of the air-
ship and one, two or more further pro-
pellers in rear of the first, each succeeding
propeller being situated at a greater dis-
tance from the side of the airship than the 30
preceding one.

5. In an airship as claimed in claim 1,
30 guns mounted on adjustable platforms ex-
tending from the lower portion of the sides
of the framework in such a manner that 35
the guns can be fired at objects vertically
above or below the airship, substantially
as described.

In testimony whereof, I have affixed my
signature.

ARNOLD HENRY SAVAGE LANDOR.
